UNITED STATES PATENT OFFICE.

ALFRED BARKER, OF RICHFIELD SPRINGS, NEW YORK.

CLOTHES-WRINGER.

SPECIFICATION forming part of Letters Patent No. 235,491, dated December 14, 1880.

Application filed March 13, 1880. (No model.)

To all whom it may concern:

Be it known that I, ALFRED BARKER, of Richfield Springs, in the county of Otsego and State of New York, have invented certain new and useful Improvements in Clothes-Wringers; and I do hereby declare that the following is a full, clear, and exact description of the construction and operation of the same, reference being had to the annexed drawing, making a part of this specification, and to the letters and figures of reference marked thereon.

The figure of the drawing is a representation of a side elevation, partly in section, of my clothes-wringer.

My invention relates to clothes-wringers; and it consists in the features of construction and combination of parts as hereinafter fully set forth, and particularly pointed out in the claim.

A designates the base, upon which are supported two standards, B B. C C are the rolls, which are journaled in grooves D of the standards, and E E are the anti-friction rollers, which bear upon the journals of the rolls C.

The anti-friction rollers have journals E', which project into the grooves D of the standards, and each pair of rollers is connected by a rod, F, the ends of which are loosely journaled in the said anti-friction rollers. The standards are hollow, or are provided with tubes extending from their top ends down to their slotted portions, as illustrated in the sectional view, these hollow parts being for the reception of spiral springs G. To depress these springs upon the journals of the upper pair of anti-friction rollers, so as to cause said rollers to bear upon the journals of the wringer-rolls, and thus tighten up the said rolls, the following means are provided:

H is a cross-bar secured to the tops of the standards, and formed with holes to admit of the passage of pins I I down into the hollow

standards and against the springs. The pins I I are secured to the ends of the levers K K, 45 which are pivoted at about their central parts to the bar H. The adjacent ends of these levers rest upon a ring, L, which fits loosely upon a set-screw, M, and so as to rest upon a collar, N, formed with or secured to the screw. 50 This screw passes down through the bar H, and is provided, at its upper end, with a hand-wheel, M'. In raising the screw the inner ends of the levers are raised by the ring upon which they rest, while their outer ends are 55 consequently depressed, so as to force the pins upon the springs. In thus compressing the pins they act upon the journals of the upper pair of anti-friction rollers, and these said rollers, acting upon the journals of the upper 60 wringer-roll, cause them to be forced closer against the lower wringer-roll, the journals of which rest upon the lower pair of anti-friction rollers.

Having thus described my invention, what 65 I claim is—

The combination of the upper one of the wringer-rolls C, the grooved and hollow standards, the upper pair of anti-friction rollers E, with journals E' projecting into the standards, the springs G, arranged within the standards and bearing upon the journals E of the anti-friction rollers, the cross-bar H, the pivoted levers K, with pins passing through the cross-bar into the standards, the screw M, with 70 a collar, N, and the ring L, arranged upon the screw below the inner ends of the levers, substantially as and for the purpose set forth.

In testimony that I claim the above I have hereunto subscribed my name in the presence 80 of two witnesses.

ALFRED BARKER.
